UNITED STATES PATENT OFFICE.

EDWIN T. PETERS AND DAVID B. HOWARD, OF LINCOLN, NEBRASKA, AND JOHN M. MURRAY, OF MINNEAPOLIS, MINNESOTA.

WINDOW-SASH HOLDER.

1,185,239.

Specification of Letters Patent.

Patented May 30, 1916.

Application filed January 13, 1915. Serial No. 1,938.

To all whom it may concern:

Be it known that we, EDWIN T. PETERS, DAVID B. HOWARD, and JOHN M. MURRAY, citizens of the United States, the said EDWIN T. PETERS and DAVID B. HOWARD residing at Lincoln, in the county of Lancaster and State of Nebraska, and the said JOHN M. MURRAY residing at Minneapolis, in the county of Hennepin and State of Minnesota, 5 have invented certain new and useful Improvements in Window-Sash Holders; and we do hereby declare the following to be a full, clear, and exact description of the invention, such as will enable others skilled 10 in the art to which it appertains to make and use the same.

Our invention relates to windows having sliding sash, and has for its object to provide an improved sash holder adapted for 20 use as a substitute for the ordinary weights and cords.

Generally stated, the invention consists of the novel devices and combinations of devices hereinafter described and defined in 25 the claims.

In the accompanying drawings which illustrate the invention, like characters indicate like parts throughout the several views.

Referring to the drawings: Figure 1 is a 30 view in elevation with some parts broken away and some parts sectioned, looking at the inner face of a window frame and its sash; Fig. 2 is a vertical section taken on the line $x^2 x^2$ on Fig. 1; Fig. 3 is a vertical section taken approximately on the line $x^3 x^3$ on Fig. 2, some parts being shown in full; Fig. 4 is an enlarged horizontal section taken approximately on the line $x^4 x^4$ on Fig. 1, some parts being shown in full; 35 Fig. 5 is a horizontal section taken on the line $x^5 x^5$ on Fig. 1; and Fig. 6 is a detail in section on the line $x^6 x^6$ on Fig. 5.

The window frame 1 may be of any suitable construction, but need not have the 40 weight boxes which are ordinarily provided for windows wherein weights are employed.

The numerals 2 and 3 indicate, respectively, the upper and lower sliding sash which, except as hereinafter noted, are of 45 the usual construction, and are confined for vertical sliding movements in the frame 1, by means of ordinary inside, outside and intermediate guide strips 4, 5 and 6, respectively.

50 In accordance with our invention, the

sash 2 and 3, in their vertical edges, are formed with channels 7 that increase in depth toward the bottom of the said sash. The channels 7 of the lower sash extend completely from the bottom to the top 60 thereof, while the channels 7 of the upper sash extend completely to the top, but preferably terminate slightly short of the bottom thereof, (see particularly Fig. 2).

Arranged to run in the channels 7 and to 65 press tightly against the bottoms thereof are anti-friction presser wheels 8 mounted on the ends of the prongs 9, which latter work in tubular sockets 10, and have square shanks 11 that work through square perforations in 70 the extreme ends of the said sockets. These square shanks hold the rollers 8 in true alinement with the channels 7 and prevent rotation of the plungers within the sockets. The said sockets, at their open ends, are provided with vertically bent flanges 12 that 75 are set in flush with the inner faces of the upright portions of the window frame 1 and are rigidly secured thereto, preferably by screws. Coiled springs 13 which surround 80 the stems 11 and are compressed between the ends or bottoms of the said sockets 10 and the shouldered portions of the prongs 9, yielding, but quite tightly press the wheels 8 against the bottom of the respective 85 channels 7.

As is evident, the yieldingly pressed wheels 8, acting against the upwardly diverging bottom surfaces of the opposite channels 7, not only tend to hold the respective sash against vertical downward movements, but have a tendency to cause the same to rise. This tendency to rise, however, is not, in itself, sufficient to actually raise the sash, but it makes the upward sliding movement of the sash an easy matter. In the bottoms of the channels in which the upper sash works, are stop blocks 14 preferably secured in position by screws, and in the upper extremities of the channels in which the lower sash works, are similar stop blocks 15 also preferably secured in position by screws. The lower stop blocks 14 prevent the upper sash from being moved downward far enough to carry the sash below the co-operating upper presser wheels 8, and the upper stop blocks 15 prevent the lower sash from being moved upward above the co-operating lower presser wheels 8. When, 90 however, the said stop blocks are removed, 95 100 105 110

which may be easily done, the upper sash may be moved downward below the coöperating rollers 8, and the lower sash may be moved upward above their coöperating rollers 8, so that when the outer and inner stop strips 4, respectively, are removed, the said sash may be easily taken out of the window frame.

These improved sash holding devices, so-called, may be applied either to new or to already built in windows, at small cost. In fact, they may be applied at a less cost than the ordinary weights and cords, and furthermore, make unnecessary the weight receiving box structures of the frames, and thus effect a further saving in the cost of new construction.

What we claim is:

The combination with a window frame and a sash mounted to slide vertically therein, said sash having in its opposite edges

channels, the bottoms of which diverge upwardly, of sockets set into the sides of said window frame, spring-pressed plungers in said sockets provided with wheels arranged to run in said channels and to press against the bottoms thereof, the said channels running to at least one vertical extremity of said sash, and the said rollers being so located that the sash, in one extreme position, may be moved beyond the same, and stops normally preventing movement of the said sash beyond said wheels.

In testimony whereof we affix our signatures in presence of two witnesses.

EDWIN T. PETERS.
DAVID B. HOWARD.
JOHN M. MURRAY.
